CLAIM

The ornamental design for a bicycle kickstand support, as shown and describe.

DESCRIPTION

FIG. 1 is a perspective view of a bicycle kickstand support showing our new design in solid lines;

FIG. 2 is a bottom view thereof;

FIG. 3 is a cross-sectional view thereof taken along lines 3—3 of FIG. 1;

FIG. 4 is a front elevational view thereof with a portion broken away at the top, and with the rear elevational view being identical; and,

FIG. 5 is a side elevational view taken of either side thereof with a portion broken away at the top, it being understood that the righthand and lefthand side views are identical. The broken lines shown in FIG. 1 are for illustrative purposes only and form no part of the claimed design.
